CARTRIDGE HOLDER

Robert N. Farquharson, Bradford, Pa., assignor to W. R.
Case & Sons Cutlery Co., Bradford, Pa.

Filed Oct. 16, 1972, Ser. No. 300,115

Term of patent 14 years

Int. Cl. D22—05

U.S. Cl. D22—14

FIG. 1 is a general front elevational view of a cartridge holder showing my new design;

FIG. 2 is a top plan view thereof;

FIG. 3 is a bottom plan view thereof; and

FIG. 4 is an end elevational view taken from the left end of FIG. 1.

I claim:

The ornamental design for a cartridge holder, substantially as shown.
